UNITED STATES PATENT OFFICE.

JULIUS D. TSCHOPIK AND NELSON G. GOREAU, OF NEW ORLEANS, LOUISIANA.

FLUSHING DEVICE.

No. 870,597.

Specification of Letters Patent.

Patented Nov. 12, 1907.

Application filed October 27, 1904. Serial No. 230,275. Renewed July 10, 1906. Serial No. 325,513.

To all whom it may concern:

Be it known that we, JULIUS D. TSCHOPIK and NELSON G. GOREAU, citizens of the United States, residing at New Orleans, in the parish of Orleans and State of Louisiana, have invented new and useful Improvements in Flushing Devices, of which the following is a specification.

Our invention relates to flushing devices for water closets, and its object is to simplify and improve the construction of devices of this kind.

In its preferable form the invention is embodied in the device set forth in the following description and accompanying drawings.

In the drawings: the figure shown is a central vertical section of the device.

Referring to the drawings, A is the body of the valve casing. It has an inlet opening B and an outlet pipe C, the latter leading to the bowl.

Mounted on the pipe C is an operating lever D having an arm E mounted within the pipe and adapted to bear against a stem F to which is secured a pilot valve G. The pilot valve is held yieldingly on its seat by a coiled spring H surrounding the upper part or stud I of the valve stem. The upper end of the coiled spring surrounds a downwardly projecting stud J which is provided with a threaded head K engaging screw threads on the interior of a main flushing valve L. The screw stud J serves as means to adjust the tension of spring H.

The pilot-valve G is adapted to close and open port G¹ which serves to establish communication between the interior of the main valve and the outlet pipe C.

The flushing valve is provided at its lower end with a rubber or leather washer M adapted to seat on the valve casing, and the valve is adapted to control the communication between the inlet B and the outlet pipe C. Secured to the valve L is a skeleton cage N which moves in the pipe C and serves as a guide for the valve L and also to guide the valve stem F.

Clamped in the upper end of the valve L, by a threaded washer O is a flexible diaphragm P, preferably of rubber, which is clamped around its edge to the casing by screws Q passing through the annular flange of an inclosing cap or cover R. An air and water chamber S is formed by and between this cap and the diaphragm. This chamber communicates with the interior of the valve L by holes or passage ways T formed in the screw-stud J. In the cap R is a screw trap U for permitting ready access to the chamber S. Depending from this trap is an adjustable stop-screw V, adapted to limit the upward movement of the diaphragm and which may be adjusted to regulate the extent of said movement.

The chamber S communicates with the inlet B by a small pipe or passage way W, in which is mounted a regulating valve X, consisting of a screw extending

against the beveled seat Y in the pipe or passage way W, the upper end of the pipe or passage way, which is extended into the cap R, being provided with a closing screw Z.

The operation of the device is as follows: Upon raising the lever D and arm E, the valve stem F will be raised and the valve G raised from its seat in the main valve L. Thereupon the water will be permitted to escape from within the main valve and from the chamber S into the outlet pipe C. This escape of the water will relieve the pressure in the chamber S on the diaphragm, and the latter will be raised by the pressure of the water from the inlet, carrying up with it the main flushing valve L which thereby establishes communication between the inlet B and the outlet C and the water rushes into the bowl. At the same time water from the inlet will pass in a comparatively small quantity through the passage way W into the chamber S. The flushing valve L will remain open and the flushing action be continued until the chamber S is filled with the incoming air and water and the diaphragm forced out and down so as to seat the valve L and close communication between the inlet and outlet. The length of the flushing may be regulated by the adjustment of the screw X, which may be screwed down or up to lessen or increase the size of the passage and thus regulate the flow of the water passing into the chamber and consequently the length of time of the flushing action.

The inlet B may be connected either to a tank or directly to a water main.

It is clear that various changes in the details of the device may be made without departing from the principle of our invention.

Having thus described our invention, what we claim is:

1. The combination of a substantially cylindrical casing, a discharge pipe leading substantially centrally from the bottom of the casing, a main valve seat at the top of said discharge pipe, a hollow main valve resting on said seat, a diaphragm secured to the top of said main valve, a cover securing the diaphragm to the casing, a guide cage reciprocable within the discharge pipe and connected to the main valve for directing its movement, a pilot valve seat within the main valve, a pilot valve resting on said seat and having a stem passing through and to a point below the guide cage, a spring resting upon the pilot valve, and an adjusting screw near the top of the hollow main valve forming an abutment for the spring and providing means of adjustment for the same.

2. The combination of a substantially cylindrical casing, a discharge pipe leading substantially centrally from the bottom of the casing, a main valve seat at the top of said discharge pipe, a hollow main valve resting on said seat, a diaphragm secured to the top of said main valve, a cover securing the diaphragm to the casing, a guide cage reciprocable within the discharge pipe and connected to the main valve for directing its movement, a pilot valve seat within the main valve, a pilot valve resting on said seat and having a stem passing through and to a point below the guide

cage, a spring resting upon the pilot valve, an adjusting screw near the top of the hollow main valve forming an abutment for the spring and constituting means of adjustment for the same, and a screw trap in the cover 5 movable to permit adjustment of the spring.

3. The combination of a valve casing, a discharge pipe, an inlet pipe, a hollow main valve within the casing, a guide cage therefor movable in the discharge pipe, a diaphragm connected to the main valve, and dividing the 10 casing into an upper and a lower part, a by-pass leading from the inlet to the upper part of the casing, a pilot valve within the hollow main valve, a spring holding the pilot valve normally on its seat, a perforated screw member in the main valve, serving as an abutment for the 15 spring, as adjusting means therefor, and permitting fluid to pass from the upper part of the casing to the interior of the main valve, and a stem on the pilot valve extending through the guide and below the guide cage, and a finger actuated from outside the casing and adapted to raise the 20 stem of the pilot valve.

4. The combination of a casing, a hollow main valve therein and free from the casing, a diaphragm connected to said valve and the casing, a tubular member communicating with the casing, a guide cage movable in said tubular member and connected to the main valve serving to 25 guide said valve, an auxiliary valve within the main valve, a spring for closing the auxiliary valve, and a perforated abutment carried in the bore of the main valve serving to hold the spring against the auxiliary valve.

30 5. The combination of a casing, a hollow main valve

therein and free from the casing, a diaphragm connected to said valve and casing, a tubular member communicating with the casing, a guide cage movable in said tubular member and connected to the main valve serving to guide said valve, an auxiliary valve within the main valve, a 35 spring for closing said main valve, and an abutment for the spring adjustable in the main valve for regulating the action of the spring.

6. The combination of a casing, a tubular member communicating with the casing, a main valve seat thereon, a 40 hollow main valve within and free from the casing and seating on said main valve seat, a guide cage connected to the main valve and movable within the tubular member, an auxiliary valve seat within the main valve, an auxiliary valve seating thereon, a spring tending to set the 45 auxiliary valve, and an abutment adjustable within the main valve for regulating the pressure of the spring.

7. In devices of the character described, the combination of a hollow main valve, a valve seat therein, an auxiliary valve normally resting on the seat, a spring urging 50 the auxiliary valve to normal position, and an abutment for the spring adjustably mounted in the main valve.

In testimony whereof we have hereunto affixed our signatures.
